(57) CLAIM

The ornamental design for a hood for work machine, as shown and described.

DESCRIPTION

FIG. 1 is a front view of the hood for work machine showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is an enlarged cross sectional view thereof taken along line 7—7 in FIG. 1;

FIG. 8 is an enlarged cross sectional view thereof taken along line 8—8 in FIG. 1;

FIG. 9 is a perspective view thereof;

FIG. 10 is a reference front view thereof shown in use condition; and,

FIG. 11 is a reference perspective view thereof shown in use condition.

The broken line showing of a work machine in FIGS. 10 and 11 is included for the purpose of illustrating environmental structure and forms no part of the claimed design.
